PORTABLE MAT

Noah S. Harter, Waukegan, Ill., assignor to The American Steel and Wire Company of New Jersey, a corporation of New Jersey

Application March 12, 1942, Serial No. 434,419

4 Claims. (Cl. 94—13)

This invention relates to removable mats, and particularly to an improved portable mat especially adaptable as a landing field mat for use in landing aeroplanes and the like, and to a method of assembling the same.

It is one of the objects of the present invention to provide an improved portable mat which is simple and inexpensive in its construction and use, and, at the same time, one that is quickly assembled for use, or dismantled.

It is another object of the invention to provide an improved portable mat which is strong and rugged in its construction and one which is relatively light in weight, thereby making it readily transportable from one point to another.

It is a more specific object of the present invention to provide a portable mat consisting of a plurality of chain link fabric panels or sections connected together by an improved fastening means, so as to provide a mat having a substantially flat continuous surface which is especially adaptable for use as an aeroplane landing field mat.

It is a further object of the invention to provide a portable mat which is composed of panels or sections that are flexible in the direction of vehicular movement on the mat so that it can react to any suddenly applied forces, such as the impact of the wheels of a moving vehicle, in such a manner that no permanent set will be formed in the mat structure but that the mat will immediately restore itself to its original form after the impact.

Various other objects and advantages of this invention will be more apparent in the course of the following specification, and will be particularly pointed out in the appended claims.

In the accompanying drawings there is shown, for the purpose of illustration, an embodiment which my invention may assume in practice.

In these drawings:

Figure 1 is a plan view of the improved portable mat of my invention;

Figure 2 is a section taken on line II—II of Figure 1;

Figure 3 is a plan view of the section shown in Figure 2;

Figure 4 is a section taken on line IV—IV of Figure 1;

Figure 5 is a plan view of the section shown in Figure 4;

Figure 6 is a section taken on line VI—VI of Figure 1;

Figure 7 is a plan view of the section shown in Figure 6;

Figure 8 is a detail view showing the construction of the spiral wires of the wire fabric sections from which my improved mat is made;

Figure 9 is an end view of Figure 8;

Figure 10 is a detail view showing one of the fastening members for connecting the sections together; and

Figure 11 is a side view of Figure 10.

Referring more particularly to the drawings, the improved portable mat of my invention consists of a plurality of substantially flat chain link flexible fabric panels or sections 2 adapted to be laid in substantially abutting relation to each other. The panels or sections may be laid with the side edges of adjacent panels either actually abutting or spaced a slight distance apart, preferably not over 2 inches apart. Each of the flat panels or sections 2 consists preferably of a plurality of steel wires 3 shaped in the form of oval spirals and coiled together, as shown in Figures 8 and 9 of the drawings, to form a continuous reticulated flexible panel commonly known in the fence art as chain link fabric. For example, a very practical section for use, as shown in the drawings, consists of a panel about 10 feet wide and 300 feet long, consisting of steel wires 3 formed into oval spirals which, when linked together, will provide a substantially flat panel or section having square or diamond-shaped meshes.

While the panels or sections 2 may be constructed to form meshes of any desirable dimensions, I have found a mesh of $2\frac{1}{4} \times 2\frac{1}{2}$ inches to be a desirable and preferred size using a wire of approximately No. 6 gauge which is .192 of an inch in diameter. While panels 10 feet wide by 300 feet long are preferred, it will be possible, when using chain link fabric as described, to make the panels any desirable width, depending upon the length of the spirals selected. Also, the length of a panel can be varied as desired by inserting a spiral wire link member between two panels so as to connect two smaller panels to form a larger panel.

As shown in Figures 1, 5, 7, 10, and 11 of the drawings, there is arranged, along each of the opposed abutting side edges of the mesh panels or sections 2, a plurality of link-like fasteners 4 spaced approximately 6 inches apart. These fasteners are preferably in the form of straight rods about $\frac{1}{8}$ of an inch in diameter and approximately $6\frac{1}{2}$ inches long and are provided with a hook or eye portion 5 and 6 at each end thereof. The inner eye or hook 5 is substantially closed and attached to the chain link fabric at the intersection of two adjacent spiral wires thereof at

a distance of approximately one and one-half meshes in from the side edge of the panel. The straight portion of each of the fasteners is arranged to extend from the point of anchorage of the inner hook portions 5 out through the oval space formed by one of the spirals to the edge or slightly beyond the edge of the panel or section to which the hooks are attached. That is, the straight portion of each of the fasteners 4 is disposed within the oval spirals of the steel wires 3 forming the fabric of the section, so that the movement of the fasteners is confined, and free movement of the fasteners is thus prevented. The outer eye or hook portion 6 of each of the fasteners is preferably bent in a plane substantially at right angles to the plane in which the inner eye or hook portions 5 are bent and each of the outer eyes or hooks is opened a sufficient space to permit the insertion of a wire rope 16 in a manner hereinafter to be described. Each of the outer eye or hook portions 6 is preferably bent so as to present the open space of the hook either to the upper or lower side of the panel or section of the mat, or they may be bent into the same plane, either to the right or to the left of the inner hooks and in the same plane as the plane of the chain link panels or sections in which the inner hook portions 5 are bent. By attaching the hooks or fasteners to the panels in the manner described, any forces exerted by the fasteners, due to a pull on the same by the impact of a vehicle moving on the mat, will be transmitted to the true horizontal axis of the fabric, thereby transmitting a uniform pull on the fabric and preventing any side pulls and consequent concentration of stresses and formations of undesirable sets or permanent distortion of the fabric of the panels.

A series of panels or sections 2 as described are then laid together side by side in substantially abutting relationship to form an aeroplane landing mat of any width and length desired. Adjacent panels or sections 2 having the hook or fasteners 4 attached to the side edges thereof are so laid that the fasteners 4 are arranged in a staggered relationship, as shown in Figure 7, and the adjacent panels are connected together by inserting a wire rope or cable 16 into the open hook portions 6 of all of the fasteners 4 so that adjacent sections or panels are connected to the wire rope or cable therebetween and successively to each other. For this purpose I prefer a $\frac{1}{2}$ inch flexible steel rope, known in the art as "Plow steel hoisting" grade.

By thus anchoring the inner hook portions 5 of the fasteners 4 in the manner described, that is, a distance equaling approximately one and one-half meshes of the fabric in from the edge of the fabric section, the shank or straight portion of the fasteners 4 is confined by intersections of the spiral wires at both sides of the shank in a position parallel to the longitudinal axis of the spiral wires 3 of the chain link fabric and substantially perpendicular to the sides of the panels 2 so that the outer open hooks 6 are prevented from swinging out of line and are held in a substantially fixed position readily accessible for the lacing of the wire rope elements into the hooks during the assembling of the sections or panels 2.

The ends of the wire spirals 3 forming the panels or sections 2 are preferably knuckled over in pairs, as shown at 7 in Figures 5 and 7, to hold the wire spirals securely together in the position in which they are linked. All of the wires forming the panels or sections 2 and the hooks or

fasteners are preferably galvanized or otherwise coated so as to render the mat resistant to corrosion.

The end of the stock or wire defining the open space of the outer hook portion 6 of each of the fasteners 4 is preferably rounded or chamfered so as to present a rounded edge for facilitating the insertion of the wire rope elements 16 into the hooks. Thus, in the event the fasteners are attached to the fabric with the open hook portions 6 bent perpendicular to the horizontal plane of the mat, with the open hook portions 6 turned upwardly, the rounded or chamfered edge portions on the end of the hooks of the fasteners will be presented so as to minimize any injury to the wheels of the vehicles operating on the mat. It is preferable, however, that the fasteners 4 be secured to the panels so that the open hook portions 6 are bent downwardly from the face 20 of the mat whereby, if the hook portion is pulled out straight by a sudden impact on the mat, the straightened hook portion will be projected down into the earth on which the mat is laid.

The portable mat of my invention is assembled in the following manner:

25 The mesh panels or sections 2 are arranged in the desired position with their side edges substantially abutting as shown so that the longitudinal axis of the spiral wires of adjacent panels are parallel to and coincide with each other and so that they are parallel to and coincide with the general direction the aeroplanes or vehicles are adapted to move over the mat.

By such an arrangement, a maximum flexibility of the panels comprising the mat is obtained, so that, as the wheels of an aeroplane or vehicle move along the mat, the spiral wire elements will readily flex or pivot at the points where the spirals are linked together, without unduly straining or placing a set in the fabric of the panel. After the wheels of the vehicle have passed over a section of the mat, the wire spirals of that section will return to their original position, due to the pivoting or hinging action of the 45 chain link fabric construction, unless the wires are held down in their distorted position by other agencies, such as soft earth or sand into which the mat may have been pressed by the wheels of the vehicle, in which case, if desired, the mat 60 can be pulled up out of the sand so as to restore it to its original position.

When the first panel or section 2 defining the mat is laid, it is subjected to a preliminary or nominal tension so that the side edges will be straight. The panel is stretched by tensioning means 8 provided at each end of the panel and spaced approximately 2 feet apart, as shown in Figures 1 and 2 of the drawings. This tensioning means, as shown in Figures 2 and 3, consists preferably of a series of rods 10 with hook portions 11 arranged on the inner end thereof for attaching the ends of the same to the panels or sections 2. There are provided preferably stretcher bars 9 which are disposed in the outer edges at the ends of the panels and to which the hooks 11 of the rods 10 are connected, so as to enable the rods 10 to exert a uniform pull on the panel and prevent the formation of concentrated stresses therein. The bars 9 are laid preferably in the oval space in the outer wire spiral of the panels, substantially parallel to the longitudinal axis of the outer wire spirals thereof.

The rods 10 are preferably threaded on the ends opposite the hook portions 11 and have nuts 12 and washers 12a arranged thereon. There is

provided preferably a U-bar drive stake 13 for each tension device 8 which is driven into the ground, as shown in Figure 2, so as to anchor the panels 2 at the ends thereof. These U-bars are driven into the ground at a point intermediate the ends of the tension rod 10 and have a hole drilled in the upper portion thereof through which the rod 10 is inserted. A coil spring 14 and spring protecting cover 15 are arranged on each rod 10. The springs 14 maintain the panels under tension and the amount of tension is adjusted by means of the nuts 12. The tensioning devices 8 are preferably buried in the ground in the manner shown so as not to present any obstacles for vehicles that may pass over the edge of the mat.

After one panel or section 2 has been laid and given nominal preliminary stretch to straighten the sides thereof, a second panel 2 is laid adjacent and in abutting relation to the first panel and the second panel is then given the same nominal stretch to straighten the sides thereof and to present the hooks or fasteners 4 in the side edges thereof in a staggered relationship to the hooks or fasteners secured in the adjacent side of the first panel or section 2. Thereafter the rope or cable 16 is laced in the open hooks 6 of the fasteners 4 in the abutting sides of the two adjacent panels, whereupon the rope is pulled taut to draw the two panels together and into position as shown in Figures 1 and 7. Tensioning means similar to tension devices 8 used at the ends of the panels 2 are preferably used to tension the rope or cable 16 which can be attached to both ends of the rope by means of eyes 17 formed in the ends of the rope element and held by any ordinary type of rope or cable clip as shown in Figures 6 and 7. These tensioning devices for the rope or cable are likewise preferably buried in the ground so as not to leave any obstruction above ground to impede moving vehicles.

After the second panel or section 2 has been laid, a third panel may be laid and given a preliminary stretch or tension and a second cable may be laced into the hooks of the fasteners secured in the adjacent side edges of the second and third panels after which the cable can be pulled tight to draw the sides of the panels together, care being taken to maintain the sides of the panels straight at all times. Additional panels can thereafter be laid in place and similarly tensioned and secured in place until the entire mat has been laid. After a number of panels have been laid, additional tension can be applied to the ends of the panels beyond the nominal tension originally applied, beginning with the first one, to pull them as taut as may be desired and necessary.

There are also provided similar hooks or fasteners 4 in the outer sides of the two end panels of the landing mat with tension devices provided for each hook spaced approximately 12 inches apart, as shown in Figures 1, 4, and 5, similar to the tension devices 8 arranged at the ends of the panels for tensioning the mat in a longitudinal direction.

It will be understood that while my improved mat is especially adaptable for use as a landing field mat for aeroplanes and the like, it may be used for any purpose wherein it is desired to provide a flat surface on relatively soft earth, such as a passageway for any other type of vehicle.

As a result of my invention, it will be seen

that there is provided an improved portable mat consisting of a plurality of panels or sections of chain link fabric, with each portion of the sections being capable of being flexed out of the plane of the mat, due to forces or impacts to which the mat may be subjected in use, without permanently distorting or causing the formation of permanent sets in the fabric of the mat and thereby maintaining the latter uniformly flat at all times.

By my invention, I have provided an improved portable unitary mat having panels or sections which are positively secured together and yet provide a flexible joint, with the connecting or fastening means confined within the upper and lower surfaces of the panels or sections.

It will also be seen that the mat can be quickly dismantled, if desired, and transported from one point to another by merely unlacing the wire rope elements from the abutting edges of the sections and detaching the anchoring means provided at the end and side edges thereof, thereby providing a mat which is serviceable and one which can be quickly assembled and dismantled.

While I have shown and described a particular embodiment of my invention, it will be understood that I do not wish to be limited exactly thereto, as various modifications and changes may be made without departing from the scope of the invention, as defined by the appended claims.

I claim:

1. A portable mat of the class described comprising a plurality of substantially flat sections of woven chain link fabric formed of wire spirals, said sections adapted to be laid in substantially abutting relation for rapid attachment and detachment to each other with the longitudinal axis of the wire spirals in each section laid substantially perpendicular to the abutting edges of said sections, a plurality of spaced apart fastening members arranged along the abutting edges of each of said sections, a flexible member arranged between the abutting edges of each of said sections and extending throughout the length thereof, each of said fastening members having means arranged on one end thereof for connecting the same to said flexible member and means arranged on the opposite end for connecting the same to the link fabric at the intersection of two of the spiral wires thereof with each of said fastening members extending into the convolutions of the wire spirals of the link fabric so as to be disposed substantially parallel to the longitudinal axis of the wire spirals and confined therewithin substantially in the plane of the fabric, a bar arranged through the convolutions of the outermost wire spiral at each side of each of said sections substantially parallel to the longitudinal axis of the wire spirals, means attached to said bar for stretching and anchoring the same at the sides of said mat, and means connected to both of the endmost sections of the mat for stretching and anchoring the same at the ends thereof.

2. A portable mat of the class described, as defined in claim 1, wherein the means arranged on each end of each of the fastening members for connecting the same to the flexible member and to the link fabric consists of a substantially hook-shaped portion.

3. A portable mat of the class described consisting of a plurality of sections of woven chain link fabric formed of spiral wires which are adapted to be laid in substantially abutting relation for rapid attachment and detachment to

each other, a plurality of spaced apart fastening members arranged along each of the abutting edges of each of said sections with each of said fastening members extending into the convolutions of the wire spirals of the link fabric so as to be confined therewithin substantially in the plane thereof, and a longitudinally extending flexible member arranged between the abutting edges of each of said sections to which said fastening members are attached so as to provide a continuous unitary mat, each of the fastening members consisting of a link-like member having a hook-shaped portion arranged in each end thereof with one of the hook-shaped portions connected to the wire fabric at the intersection of two of the spiral wires thereof, and the other hook-shaped portion connected to the flexible member.

4. A portable mat of the class described consisting of a plurality of sections of woven chain link fabric formed of spiral wires which are

adapted to be laid in substantially abutting relation for rapid attachment and detachment to each other, a plurality of spaced apart fastening members arranged along each of the abutting edges of each of said sections with each of said fastening members extending into the convolutions of the wire spirals of the link fabric so as to be confined therewithin substantially in the plane thereof, and a longitudinally extending flexible member arranged between the abutting edges of each of said sections to which said fastening members are attached so as to provide a continuous unitary mat, each of the fastening members consisting of a link-like member having one end thereof confined within the spiral wires of the fabric and connected to the fabric at the intersection of two of the spiral wires thereof with the opposite end of the fastening member connected to said flexible member.

NOAH S. HARTER.
